APPARATUS FOR RECORDING AND REPRODUCING SOUNDS

Louis Paul Durand and Pier Carlo Ricchiardi,
Paris, FranceApplication September 17, 1935, Serial No. 40,984
In France January 10, 1935

7 Claims. (Cl. 179—100.4)

There exists apparatus intended to be used both for recording and reproducing sounds in which a single pick-up is employed for these two different functions.

Now these two different functions compel the person that is using the apparatus to make the following multiple operations:

- 5 1. To modify the weight of the pick-up;
2. To operate the clutch mechanism through which the arm of the pick-up can be coupled with the driving mechanism;
- 10 3. To operate the contactor that controls the recording and reproducing circuits.

These multiple operations complicate the use 15 of the apparatus and the person that is using the apparatus may make mistakes which, in particular, may impair the recording.

The object of the present invention is to obviate these drawbacks and to provide an apparatus of the type above referred to including a single organ for controlling the electrical and mechanical characteristics of the pick-up in either of its recording and reproducing functions, thus avoiding any risk of a mistake of the 25 person that is using the apparatus.

According to a feature of the invention, this single operating organ controls, on the one hand, the clutch device associated with the driving arm of the pick-up, and, on the other hand, an electric 30 switch capable of connecting the pick-up either with the recording circuit (radio transmission, microphonic current, telephonic line, etc.) or with the reproduction circuit (amplifier and loud speaker).

In a preferred embodiment of the invention, the single operating organ is combined with an adjusting organ which varies the weight of the pick-up in accordance with the function that is to be performed by the apparatus (sound 35 recording or reproduction), whereby the pick-up is always placed in the physical condition that corresponds to its maximum efficiency in either of its two functions.

Other features of the present invention will 40 result from the following detailed description of a specific embodiment thereof.

A preferred embodiment of the present invention will be hereinafter described with reference to the accompanying drawings, given merely 45 by way of example, and in which:

Fig. 1 is a diagrammatic elevational view, partly in section, of an apparatus including a pick-up adapted to be used both for recording sounds on phonographic discs and for reproducing said 50 sounds;

Fig. 2 is a plan view of the clutch mechanism of the arm of the pick-up;

Figs. 3 and 4 are two diagrammatical views of the single operating organ shown in two different positions respectively, corresponding to the reproducing function and the recording function, 5 respectively, of the pick-up.

The apparatus shown in the drawings includes a motor 1 the shaft 2 of which drives a circular plate 3 carrying the phonographic disc 4. The unrecorded phonographic discs on which sounds are to be recorded are preferably rigidly fixed to circular plate 3 by means of a nut 5 adapted to be screwed on the upper end of shaft 2.

Shaft 2 also controls, through an endless screw 6 and a helical gear 7, a driving screw 8 intended to produce the radial displacement of the pick-up with respect to the phonographic disc, as it will be hereinafter described.

The arm 10 of the pick-up 9 is hinged to a pivot 11 having a vertical axis, in such manner that the head of the pick-up bears, under the action of gravity, upon disc 4.

According to the present invention, a single operating organ automatically ensures the positioning of the pick-up in either of its two functions (recording or reproduction).

In the embodiment shown in the drawings, a cam 15, adapted to be actuated through a small lever 16, cooperates with an oscillating lever 17 30 the lower end of which is engaged in a notch 18 provided in the rod 19 of the clutch device.

This rod 19 carries a toothed sector 20 and it is normally urged, in the direction of arrow F, toward the driving screw 8, by the action of a spring 21.

In the position shown by Figs. 1, 2 and 3, cam 15 keeps the oscillating lever 17 in a position in which it opposes the displacement of clutch rod 19 in the direction of arrow F, so that the toothed sector 20 is out of contact with the driving screw 8.

In this position, the clutch rod 19, which carries at its rear end a fixed contact 23 connected to the coil of the pick-up, applies this contact 45 against a terminal 24 leading to the reproduction circuit (amplifying tubes and loud speaker). The needle 25 of the pick-up oscillates under the action of the groove of the record 4, and it bears upon this record with a pressure corresponding 50 to the maximum weight of the pick-up.

On the contrary, for recording sounds on an unrecorded disc, the operating lever 16 is rotated in the direction of arrow F¹, which causes cam 15 to turn into a position in which it allows le- 55

ver 17 to pivot in the direction of arrow F². Under the action of its spring 21, the clutch rod 19 thus released slides in the direction of arrow F.

This movement produces the following results (Fig. 4):

- 5 1. The toothed sector 20 is brought into engagement with the driving screw 8;
2. Contact 23 is applied against the terminal 27 leading to the recording circuit (reception of 10 radio transmissions, microphonic current, telephonic lines, etc.)
3. The upper end of the oscillating lever 17 pulls the end of an adjusting spring 30 the other 15 end of which is tied to the arm 10 of the pick-up which reduces the effect of gravity upon the 20 needle of the pick-up. The needle which cuts the sound groove into the unrecorded disc is thus 25 greatly relieved and its sound vibrations are substantially improved.
- 20 Besides, the end of spring 30 is fixed to a screw 31 screwed in a lug 32 of the arm 10 of the pick-up, which makes it possible to adjust accurately 30 the initial tension of spring 30 and to accordingly modify the desired effect.

25 Of course, while we have, in the above description, disclosed what we deem to be a practical and efficient embodiment of the present invention, we do not wish to be limited thereto as there might be changes made in the arrangement, 30 disposition and form of the parts without departing from the principle of the present invention as comprehended within the scope of the appended claims.

What we claim is:

- 35 1. An apparatus for recording and reproducing sounds which comprises, in combination, a rotary plate arranged to support phonographic discs, a pick-up adapted to bear on a phonographic disc supported by said plate, an arm for said pick-up, driving means for rotating said plate, distinct 40 electric circuits for sound recording and reproduction, respectively, mechanical means for coupling said arm with said driving means for radial displacement of the pick-up, and a single operating organ for both bringing said mechanical 45 means into or out of action and electrically connecting said pick-up with either of these two circuits, correspondingly.

2. An apparatus according to claim 1 further 50 including means, operative by said single operative organ, for varying the pressure with which the pick-up is applied against a phonographic disc carried by said plate, according as said pick-up is being employed for recording or for reproducing sounds.

3. An apparatus according to claim 1 further 55 including means, operative by said single operative organ, for varying the pressure with which the pick-up is applied against a phonographic disc carried by said plate, according as said pick-up is being employed for recording or for reproducing sounds, said means being adjustable.

4. An apparatus for recording and reproducing 60 sounds which comprises, in combination, a rotary plate arranged to support phonographic discs, a pick-up adapted to bear on a phonographic disc supported by said plate, a pivoting support rotatable about a vertical axis, an arm for said pick-

up pivoted to said support about a horizontal axis, a motor for driving said rotary plate, clutch means for coupling said pivoting support with said motor, a cam pivotally mounted in said pivoting support, a sound recording electric circuit, 5 a sound reproducing electric circuit, two terminals carried by said pivoting support connected with said circuits respectively, a contact movably carried by said support electrically connected with said pick-up, and means operatively controlled by said cam for simultaneously bringing said clutch means into or out of action and switching said contact from one of these terminals to the other one.

5. An apparatus for recording and reproducing sounds which comprises, in combination, a rotary plate arranged to support phonographic discs, a pick-up adapted to bear on a phonographic disc carried by said plate, a pivoting support rotatable about a vertical axis, an arm for 20 said pick-up pivoted to said support about a horizontal axis, a motor for driving said rotary plate, a screw operatively connected with said motor so as to be rotated by it about its axis without moving parallelly to said axis, a rod slidable 25 in said pivoting support at right angles to the axis thereof, a toothed sector at the end of said rod adapted to mesh with said screw, said rod being provided with a notch, a lever pivotally carried by said support having one end engaged 30 in said notch, a cam pivotally mounted in said support adapted to cooperate with said lever so as to maintain it in either of two positions, one for which the sector carried by said rod is kept 35 out of contact with said screw and the other for which said sector is allowed to mesh with said screw, a sound recording electric circuit, a sound reproducing electric circuit, two terminals carried by said pivoting support electrically connected with said circuits respectively, and a contact 40 carried by said rod adapted to be applied against one or the other of said terminals according as said lever is in either of said two different positions thereof.

6. An apparatus according to claim 5 in which 45 said lever is pivoted about a horizontal axis parallel to the axis about which said pick-up arm is pivoted to said pivoting support, further including a spring fixed at one end to said lever and at the other end to said arm, whereby the 50 pressure with which said pick-up bears against a phonographic disc carried by said plate varies according to the position of said lever.

7. An apparatus according to claim 5 in which 55 said lever is pivoted about a horizontal axis parallel to the axis about which said pick-up arm is pivoted to said pivoting support, further including a spring fixed at one end to said lever, and means for adjustably fixing the other end of said spring to said pick-up arm, whereby the 60 pressure with which said pick-up bears against a phonographic disc carried by said plate varies according to the position of said lever, and the values of said pressures for said respective positions can be adjusted at will.
